UNITED STATES PATENT OFFICE.

ELIZABETH M. LEEPER, OF SAN DIEGO, CALIFORNIA.

HEATING VESSEL.

No. 917, 954.

Specification of Letters Patent. Patented April 13, 1909.

Application filed June 1, 1908. Serial No. 436,021.

To all whom it may concern:

Be it known that I, ELIZABETH M. LEEPER, a citizen of the United States, residing at San Diego, in the county of San Diego and 5 State of California, have invented new and useful Improvements in Heating Vessels, of which the following is a specification.

My invention relates to improvements in that class of heating vessels as boilers or 10 bath water heaters and more particularly to be used on gas or oil stoves.

The object of my invention is to provide a vessel with large heating area and that will utilize more of the heat, thus reducing 15 the quantity of fuel usually necessary.

In the drawings Figure 1 is a vertical sectional view of my invention. Fig. 2 a top view of the same with the cover removed.

Similar characters of reference refer to 20 similar parts throughout the views.

The vessel may be annular or oblong. In this case I prefer to show and describe it as annular to be used on one fire of a gas or oil stove. The vessel 1 is annular shape and is 25 provided with a central tube 2 extending from the base centrally to the top of the vessel. On the outside of the vessel 1 and extending around said vessel is an annular passage or air space 3 which is formed by 30 extending a hood down to flush with the base of the vessel the lower edge being extended so as to cause the heat to enter the passage at 4. At the upper extremity of said passage are provided, a plurality of 35 holes 5 for the exit of the heat which enters the passage at 4.

The vessel 1 is provided with an arched

cover 6 which is provided with a central opening 7 for the exit of the heat which enters the central tube 2.

8 represents a pipe and 9 a valve which are used for the exit of the contents of the vessel.

It can readily be seen that with this construction of heating vessel that the heating 45 surface is enlarged and that the passage 3 and tube 2, confine the heat close to the heating surface of the vessel the exit area being a great deal smaller than the intake. This allows circulation and still confines the 50 heat to the vessel heating surface.

Having thus described my invention what I claim as new and desire to secure by Letters Patent, is—

In a water heater the combination of a 55 water vessel having a central tube extending from top to bottom and connecting with the lower outside surface for conveying the products of combustion through said vessel, an exterior hood or shield provided with 60 perforations at the top for the exit of heat and extending to the plane of the bottom and there flanging outward and forming a heating pocket and passage around said vessel body and a cover for said vessel provided 65 with perforations for the exit of heat all substantially as set forth.

In testimony whereof I affix my signature in the presence of two witnesses.

ELIZABETH M. LEEPER.
